UNITED STATES PATENT OFFICE.

CHARLES BOOZE, OF BUFFALO, NEW YORK, ASSIGNOR TO M. H. BIRGE & SONS,
OF SAME PLACE.

DESIGN FOR WALL-PAPER.

SPECIFICATION forming part of Design No. 20,321, dated November 18, 1890.

Application filed September 27, 1890. Serial No. 366,370. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

10 The leading feature of my design consists of a series of light and heavy parallel lines arranged vertically and horizontally over the entire surface of the paper, so as to produce the effect of the warp and woof threads of 15 cloth and represent an imitation of canvas. The heavy raised lines extend across the surface of the paper, both vertically and hori-

zontally, at unequal distances apart and form a series of squares and rectangular figures, and the light raised parallel lines fill the spaces between the heavy raised lines, forming a reticulated or net work over the entire surface of the paper, as represented in the accompanying drawing. The paper is tinted in any desired color. 25

What I claim is—

The design for wall-paper herein shown and described.

Witness my hand this 13th day of September, 1890.

CHARLES BOOZE.
